(57) **CLAIM**

The ornamental design for an optical scanner, as shown and described.

DESCRIPTION

FIG. 1 is a top plan view of an optical scanner;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top perspective view thereof;

FIG. 8 is a bottom perspective view thereof;

FIG. 9 is a top plan view of a second embodiment of an optical scanner;

FIG. 10 is a bottom plan view of the second embodiment;

FIG. 11 is a right side elevation view of the second embodiment;

FIG. 12 is a left side elevation view of the second embodiment;

FIG. 13 is a front elevation view of the second embodiment;

FIG. 14 is a rear elevation view of the second embodiment;

FIG. 15 is a top perspective view of the second embodiment; and,

FIG. 16 is a bottom perspective view of the second embodiment.

In FIGS. 9-16 the areas including stipple shading have a different contrasting color as compared to the areas that do not include stipple shading and the features shown in dashed lines form no part of the claimed design.
